CLAIM

The ornamental design for a dog house as shown and described.

DESCRIPTION

FIG. 1 is a rear perspective view of a dog house showing my new design;

FIG. 2 is a front perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

Any shading and cross-hatching are not features of the design but are utilized to illustrate the surface contours of the dog house design in the drawings.

The broken lines in the drawings illustrate portions of the dog house that form no part of the claimed design.
